UNITED STATES PATENT OFFICE.

STANLEY W. LYMAN, OF ROBERTS, MONTANA.

RAILROAD-RAIL.

941,580.

Specification of Letters Patent. Patented Nov. 30, 1909.

Application filed March 5, 1909. Serial No. 481,417.

To all whom it may concern:

Be it known that I, STANLEY W. LYMAN, a native born citizen of the United States, residing at Roberts, in the county of Carbon 5 and State of Montana, have invented new and useful Improvements in Railroad-Rails, of which the following is a specification.

The invention relates to an improvement in railroad rails, and is more particularly 10 directed to a rail made up of a series of sections adapted for assemblage in rail form to provide a practically unbroken structure.

The main object of the present invention is the provision of a railroad rail made up 15 of a series of independent sections severally including the tread portion and the base portion, the terminals of the tread sections and of the respective base sections meeting in offset planes to provide a practically unbroken rail.

Another object of the invention is the combining with a rail of the specific structure named of a chair plate adapted to embrace and clamp the base sections of the rail 25 together and support the same in the road bed, a rail tie being arranged for coöperation with the rails intermediate the terminals of adjacent chair plates to maintain the rails at proper gage.

30 The invention will be described in the following specification, reference being had particularly to the accompanying drawings, in which:—

Figure 1 is a side elevation of a rail constructed in accordance with my invention. Fig. 2 is a longitudinal section of the same taken just above the securing bolts. Fig. 3 is a perspective of one member of the base. Fig. 4 is a perspective of the coöperating 40 member of the base. Fig. 5 is a section on the line 5—5 of Fig. 2. Fig. 6 is a sectional view partly in elevation illustrating the improved rail tie used with the rail structure.

Referring particularly to the accompanying drawings, my improved rail is made up of three sections, a tread section 1, a tread supporting base section 2 and a tread clamping base section 3, both of said base sections coöperating with the tread section to form 50 the completed rail. The tread section is formed to provide the usual bar or tread portion 4, from which depends a central and longitudinally extending web 5, the under surface of the tread portion immediately adjacent and on opposite sides of the web 5 be-

ing formed to provide receiving grooves 6, as clearly shown in Fig. 5.

The base of the rail is made up of two sections for convenience termed the tread supporting section and the tread clamping section. The tread supporting section 2 is formed to provide a laterally extending base section 7, from which projects an upwardly extending wall 8 formed at the upper end to fit within one of the grooves 6 in 60 the tread portion. The wall 8 is designed to abut and snugly fit the relatively outer surface of the web 5 being formed below the web with a laterally extending shoulder 9 designed to underlie and directly engage the 65 lower edge of the web projection 5. The shoulder 9 is coextensive in width with the thickness of the web projection, and beyond said shoulder the section 2 is formed with a second shoulder 10 of somewhat less width 70 than the shoulder 9 and projected at an incline to said shoulder, said shoulder 10 being arranged below the shoulder 9. From the edge of the shoulder 10 the section 2 of the rail base is extended downward at 11 75 into a plane with the lower surface of the section and preferably at an angle to said surface, as clearly shown in Fig. 5.

The clamping section 3 of the base is formed to provide a lateral base flange 12 80 corresponding to the flange 7 of section 2 and a vertically extending wall 13 designed to fit at its upper end within the remaining groove 6 of the tread portion to snugly bear 85 throughout its length against the web projection 5 of said tread portion. The lower inner surface of the section 3 of the base is formed to engage the shoulder 10 and fit 90 against the inclined surface 11 of the section 2, whereby said parts coöperate to effectively 95 clamp the tread portion between them. In the inner surface of the section 3, at the point approximately corresponding to the relatively lower edge of the web projection 5, the section 3 is formed with a longitudinally extending groove or channel 14. This groove, when the sections are assembled, is, of course, closed by the adjacent surface of the web portion 5 and the sections 2, and is primarily adapted for the reception 100 of a bonding wire or for service as a housing for power wires. Each of the sections 2 and 3 are formed in the respective walls 8 and 13 with apertures 15, preferably arranged in a central pair and singly adja- 105 110

cent each end of the section. The outer surface of section 3, which is the inner section, between the pair of openings 15 is channeled at 16 to receive cross bars 17 of a U-shaped 5 retaining bolt 18 designed to pass through the respective sections and interposed web projection of the tread portion. By the groove and surface adjacent the openings 15 the bolt is more securely held and more 10 readily tightened. The respective sections are assembled in offset relation, that is the ends of one section, as 2, are disposed intermediate the ends of the remaining section, as 3, while the ends of the respective tread 15 portions are arranged intermediate the ends of the respective sections. The respective base sections and tread portions thus break joint throughout the entire length of the track, so that the rail is in effect continuous 20 and is not capable of transverse separation at any one determined point.

It is obvious from the construction described that when desired either of the base sections or tread portions may be removed at 25 will and substituted by others, this construction permitting the convenient renewal of either of said sections when desired and particularly the convenient renewal of the tread portion as the same becomes worn in use. 30 The rail of the present invention is designed particularly for coöperation with a road bed forming the subject matter of a concurrent application, and to particularly adapt this rail for coöperation with such bed I provide a chair plate 19 designed to 35 underlie the respective sections of the base and having inturned edges 20 to clamp over the free edges of the base flanges 7 and 12 of the respective sections 2 and 3. The relatively lower surface of the chair plate is 40 inclined in V-form, as at 21, for use with the road bed described.

In connection with the rail structure described I use a rail tie by which the respective rails are maintained at gage. This rail tie is arranged intermediate the ends of the adjacent sections of the chair plate and is adapted to directly engage the sections 2 and 3 of the base member. In detailed structure the rail tie comprises a coupling 22 having a central body 23 of angular contour in section to provide for operating the coupling by a wrench or the like. Sleeves 24 project in opposite directions from the body 23 and are interiorly threaded at 25 for the reception of tubular members 26 to the outer ends of which are fixed blocks 27 having overhanging lips 28 to engage the edges of one of the sections of the base member.

Mounted within the tubular members 26 are 60 rods 29 arranged to extend through the blocks 27 and terminate beyond the same in inclined projections 30 to coöperate with the overhanging lips 28 and to engage the free edge of the section of the base opposing the 65 section engaged by lip 28. The inner ends of the rods 29 are threaded at 31 within a threaded bore 32 formed centrally of the coupling body 23, so that by turning said body the parts may be adjusted to move the 70 rails to or from each other and thereby set the track at desired gage.

A simple means, as a yoke 33, is arranged for connection with the coupling 22 for securing said coupling against independent 75 longitudinal movement relative to the tie or other road bed structure.

The rail structure herein shown provides a sectional rail in which effective clamping of the tread portion is secured in a manner 80 to permit the convenient removal of said tread portion if desired for renewal. Furthermore, the particular chair plate described adapts the rail for coöperation with the road bed structure in a manner to prevent lateral 85 displacement of the rail while the tie member maintains the rails at effective gage throughout the length of the track.

Having thus described the invention what is claimed as new, is:—

1. A sectional rail including a base member made up of two sections, a tread portion arranged to fit between and be engaged by said sections, one of the base sections being formed to entirely underlie and support the 95 tread portion, both of said base sections being formed with coöoperating interlocking portions below the tread portion, and a chair plate underlying and clamping the sections together.

2. A sectional rail including a base member made up of two sections, a tread portion arranged to fit between and be engaged by said sections, one of the base sections being formed to entirely underlie and support the 105 tread portion, both of said base sections being formed with coöoperating interlocking portions below the tread portion, and a chair plate underlying and clamping the sections together, the lower surface of said chair plate being inclined in two distinct reversely disposed planes.

In testimony whereof I affix my signature in presence of two witnesses.

STANLEY W. LYMAN.
